UNITED STATES PATENT OFFICE.

JOTHAM S. CRUMP, OF WESTFIELD, NEW YORK.

FASTENING FOR MEETING-RAILS OF SASHES.

SPECIFICATION forming part of Letters Patent No. 319,887, dated June 9, 1885.

Application filed May 8, 1884. (No model.)

To all whom it may concern:

Be it known that I, JOTHAM S. CRUMP, a citizen of the United States, residing at Westfield, in Chautauqua county, and State of New York, have invented a certain new and useful Improved Sash-Lock, of which the following is a specification.

My invention provides a unique, simple, and inexpensive lock for the meeting-rails of window-sashes, which is absolutely proof against being opened from the outside of the window, and which requires the use of a special key or equivalent tool to open it from the inside. The moving parts, except this key, are entirely concealed within an inclosing case or shell.

Figure 1 of the accompanying drawings is a transverse section of the meeting-rails of a window provided with my lock, the section 20 cutting the lock through its center. Fig. 2 is a plan of the lock detached. Fig. 3 is an inverted plan thereof with its bottom plate removed and turned back. Fig. 4 is a section cut along the line 4 4 in Fig. 3, looking in the 25 direction of the arrow. Fig. 5 shows the bolt removed in edge view and plan, and Fig. 6 shows the key.

Let A designate the case of the lock, to be 30 screwed to the meeting-rail of the lower sash, and B the keeper or box, to be screwed to the rail of the upper sash. The case A has a bottom plate, a, fastened on it, and in the top and bottom plates are formed corresponding holes, which receive the journals b and c of a 35 disk-bolt, C. (Shown best in Fig. 5.) One side of this bolt is cut off segmentally, so that when the bolt is turned to unlock the window this side is flush with the front side of the case A, as shown in Fig. 3. To lock the window, the 40 bolt is turned, as shown in Fig. 2, and fills and closes the aperture in the face of the case, when its portion projecting beyond the case A takes under the keeper B, as shown in Fig. 1. In the construction shown the bolt C has

45 a concentric groove, d, Fig. 5, (shown in section in Fig. 1,) and on the under side of the keeper B is a corresponding rib, e, Fig. 2, also shown in section in Fig. 1. When the bolt is turned, this groove and rib interlock and 50 hold the sashes tightly together. This con-

struction, however, is not essential. The bolt is turned by means of a key, D, (shown in Fig. 6,) having a shank, f, which enters a central hole or recess, g, in the bolt, and ears h h, which engage with notches i i in the journal b. By inserting this key and turning the bolt the sashes may be either locked or unlocked, and by removing the key the lock cannot be operated without great difficulty. Thus, by hanging this key in some convenient place 55 not readily visible, and known only to the occupants of the house, an intruder in the house wishing to escape through the window will be baffled in his efforts to open the latter and his escape will be prevented or delayed, thus in 60 many cases aiding in his detection or capture. The key, instead of projecting into the bolt, may be made with a tubular shank fitting over a projecting arbor on the bolt, which it may engage by any interlocking parts. On the 65 under side of the bolt are formed two diametrically-opposite notches, j j, (shown best in Figs. 3 and 4,) and to the plate a is fastened a stiff leaf-spring, k, the free end of which engages the notches, as shown in Fig. 4, and 70 serves as a pawl to prevent the bolt being turned backward. Thus the bolt may always 75 be turned around to the right, and when the proper position is reached the spring will snap into the notch, and by bearing against the inclined side thereof will slightly resist the further turning of the bolt. This spring always generates sufficient friction against the bolt to prevent the latter being turned accidentally. One notch j will suffice, if it be the 80 one designed to hold the bolt when unlocked. When the sashes are locked and the key removed, no operative part of the lock is visible, except the journal b, and to turn the bolt without the key would require the use of a screwdriver or other similar tool. The bolt cannot 85 possibly be turned from the outside by inserting a blade through the joint between the meeting-rails.

I am aware that mutilated disk-bolts have 90 before been used in sash-locks; but invariably the mutilated disk has been made as the hub of a radial lever, which turns from side to side back and forth to lock or unlock the sashes.

I am also aware that piano-locks have been 95

made with a segmentally-mutilated disk-bolt turned by a key, and having flanges engaging the keeper, after the manner of an oscillating hook, to resist the lifting of the piano-lid. 5 These hook-bolts act in a direction at right angles to the bolt in my sash-fastener, are capable of executing only a slight oscillation back and forth, and when unlocked are incapable of wholly filling the aperture in the 10 face of the case through which they work.

I claim as my invention—

1. The combination of an inclosing-case, a disk-bolt mounted rotatively in bearings in said case and cut away segmentally on one 15 side flush with the face of the case when the bolt is in its unlocked position, a leaf-spring fixed within said case and arranged to press against said bolt and frictionally retard its movement, and a notch in said bolt arranged

to be entered by said spring when the bolt is 20 unlocked and to retain it in that position, substantially as set forth.

2. The combination of inclosing-case A, disk-bolt C, cut away on one side, mounted rotatively in bearings in the case, and formed 25 with a notch or notches, j, and a spring-pawl, k, fixed to said case and adapted to engage said notches as the bolt is turned forward and prevent its being turned backward, substantially as set forth.

In witness whereof I have hereunto signed my name in the presence of two subscribing witnesses.

JOTHAM S. CRUMP.
